UNITED STATES PATENT OFFICE.

JAMES H. MCLELLAN, OF VANCOUVER, BRITISH COLUMBIA, CANADA.

SOFT-DRINK-VENDING MACHINE.

Application filed June 29, 1923. Serial No. 648,532.

To all whom it may concern:

Be it known that I, JAMES H. MCLELLAN, citizen of the Dominion of Canada, residing at Vancouver, in the Province of British Columbia, Canada, have invented certain new and useful Improvements in Soft-Drink-Vending Machines, of which the following is a specification.

This invention relates to a machine for vending liquids, such as soft drinks, the liquid being measured to and served in a paper cup or tumbler.

The invention comprises a measuring cylinder with a piston movable in it, which cylinder receives a charge of the liquid the machine is designed to dispense from a reservoir within the machine and normally maintains it ready for delivery into a paper cup for presentation to the vendee.

20 The paper cups are nested within a magazine from which one is withdrawn coincident with the charging of the measuring cylinder.

25 The several operations involved in this delivery are performed by a handled lever outside the casing of the machine, which handled lever is operatively connected to the mechanism within the casing by the deposit of a coin of the required size in a slot provided.

30 The downward movement of the external handled lever from its normal upward position effects the expression of the contents from the measuring cylinder into the cup which has previously been withdrawn from the magazine and placed beneath the cylinder. It also moves the filled cup from beneath the measuring cylinder into position beneath the aperture through which the cup 35 is delivered for presentation to the vendee. The same downward movement places a spring or series of springs within the machine under tension, which tension restores the external operating handle to its upward 40 position, delivers the charged cup to the vendee, recharges the measuring cylinder and releases a cup from the magazine and places it in position beneath the measuring cylinder ready for filling for the next purchaser.

45 The means by which these several operations are performed is fully set forth in the following specification, reference being made to the drawings by which it is accompanied, in which:

50 Fig. 1 is a vertical section through the casing on the line 1—1 in Fig. 2, showing the

internal mechanism in elevation, the operating handled lever being shown in dot and dash lines.

Fig. 2 is a plan of the same with the upper 60 part of the casing removed.

Fig. 3 is a detail of the means by which the external operating handle is connected to the operating shaft within the machine by the presentation of a coin, the mechanism 65 being shown in the normal position.

Fig. 4 is a similar view showing the mechanism in the position where the coin is released after the required movement of the internal mechanism is effected. 70

Fig. 5 is an elevation of Fig. 3 taken in the direction of the arrow 5.

Fig. 6 is an enlarged detail showing the cup release from the magazine in section.

Figs. 7 and 8 show the cup release plates 75 of one side at the two extremes of their movement.

Fig. 9 is a cross section on the line 9—9 in Fig. 8, showing the means by which the bottom cup of the nest in the magazine is withdrawn. 80

Fig. 10 is an end elevation showing the means by which the cup release plates are operated.

Fig. 11 is a detail sectional elevation of the mechanism by which the cup is moved forward from its position beneath the magazine cylinder to the position for presentation to the vendee, and

Fig. 12 is a plan of the same. 90
The frame to which the several parts of the mechanism are connected is represented by 2, and 3 represents the casing by which the same is enclosed, which casing is provided with locked means of access which are 95 not described, as it forms no part of the invention.

In this frame 2 is rockably mounted a shaft 4 to which the several parts of the operative mechanism are connected or secured. One end of this shaft 4 (see Figs. 3, 4 and 5) projects through the side of the casing 3 and on the outwardly projecting end is rockably mounted the external handled lever 5 by which the mechanism is operated, the hub 6 of which lever passes through the casing 3. This handled lever 5 is retained on the end of the shaft 4 in any manner that will permit the handle to rock freely on the shaft without the shaft being accessible from outside the casing. Within this casing the hub 6 of the external lever 5 has a member 7 se- 100
105
110

cured on it having a tongue 8 projecting from it, which tongue is normally held by a spring 12 against the stop 10 secured to the frame of the machine to project below the lower end of a coin chute 11.

Within the casing a lever 13 is secured on the shaft 4 adjacent the inwardly projecting end of the hub 6 of the external handled lever 5. On this lever 13 is secured an extension 14 of the chute 11, which is normally held against the stop 10 and in alignment with the lower end of the chute 11 by the main operating spring 15 of the machine, (see Fig. 1), connected between the shorter end 16 of the lever 13 and the base of the frame 2. The lower end of the chute extension 14 is slotted, (see Figs. 3 and 5) to permit passage of the tongue 8.

Thus, while no coin is in the machine, the external handle 5 may be freely moved without operating the shaft 4, but when a coin of suitable size is passed into the chute 11, it will fall into the chute extension 14 and against the projection 9 on the member 7, and the coin will obstruct passage of the tongue 8 through the slot in the coin chute extension 14; and will thus form a driving connection between the external lever 5 and the shaft 4 in the direction of movement to operate the mechanism indicated by the arrow in Fig. 3. As the handled lever 5 moves upward under the tension of the spring 12, the internal operating lever 13 with its coin chute extension 14 is retained at the lower limit of its movement in a manner to be described, and the tongue 8, which moves with the lever 5 being withdrawn from contact with the coin in the chute extension 14, the coin is free to fall into a removable receptacle 17 provided, as soon as the stop 9 clears the end of the chute, as shown in Fig. 4.

A liquid measuring cylinder 18 is vertically supported in the frame 2, the lower end of which cylinder is formed with a delivery spout 19 closable with a valve 20 opening outward and held against its seat by a spring 21, the strength of which is sufficient to retain the contents in the cylinder until pressure is applied sufficient to overcome the spring.

In this cylinder 18 is movable a piston 22 to which a rod 23 is connected, which passes through the upper end cover 24 of the cylinder. Into the lower end of the cylinder 18 liquid is delivered from a reservoir 26, either by gravity or suction, through a pipe 25, a check valve 27 being in the connection of the pipe to the cylinder.

The piston rod 23 is moved downward to express the contents from the cylinder by a lever 28 pivoted at 29 to the frame 2, one end of which lever is connected by a link rod or rods 30 to the upper end of the piston rod 23, and the other end of the lever 28 is connected by a rod 31 to the shorter arm 16 of

the inside operating lever 13 of the machine which is secured on the shaft 4.

The paper cups 33, which are formed with the usual flanged upper edge, are nested within a magazine 34 in which they may freely fall. The upper edge rim of the lower cup of those in the magazine rests on the inner edges of two thin, flat plates 35 located one on each side of the cup. These plates rest on separating plates 37 which again rest on two plates 36 similar to 35. These plates 35 and 36 are retained together and are endwise and laterally moved on pins 38 secured in the frame of the machine, which pins pass through angled slots 39 adjacent each end of each plate. The slots of the lower plates are oppositely angled to those of the upper plates, (see Figs. 7 and 8), so that as the plates are endwise moved forward on the pins 38, the upper plates are constrained to recede from one another and the lower plates to approach one another, the movement being sufficient to withdraw the upper plates from the support afforded by the upper flanged edge of the cup.

The plates 35, 36 on both sides of the cup are simultaneously moved forward by the forked end 40 of a lever 41 pivoted at 42 in brackets 43 secured to the frame of the machine, the operative connection of which lever will be described later, and are normally held at the backward limit of their movement, with the upper plate 35 supporting the lower cup of the magazine, as shown in Fig. 6, by springs 44 between the ends 40 of the lever 41 which projects through the plates, and pins secured in the frame 2 (see Fig. 1).

As the plates 35, 36 are moved from this normal position, the upper plates 35 are withdrawn from support of the cup and allow the cups in the magazine to fall, and the lower plates 36, having been simultaneously moved in, afford the substitute support to the cups. As the plates 35, 36 return under the tension of the springs 44, the lower plates 36 are withdrawn releasing the lower cup, and the upper plates 35 are moved inward to support those in the magazine.

To withdraw the lower cup from the nest in the magazine when the same is relieved from support, a small wire lever 45, 46 is pivotally mounted at 47 on the outer edge of each upper plate 35, opposite the position of that plate's engagement with the cup. The inner end 45 of each lever is downwardly turned and passes through a transversely elongated aperture in each plate 35 adjacent the inner edge thereof to engage the upper side of the flanged edge of the cup as it rests on the lower plate. Normally the inner end 45 of these levers is held slightly below the upper surface of the lower plate 36 by engagement with the downwardly turned end 46 of the lever against the outer

edge of the lower plate 36, and is moved downward against the resistance of a light spring 48 secured to the back edge of the upper plate 35 as the lower plate moves outward.

The cup 33, when released from the magazine, falls on two inclined guide wires 49 secured to the underside of that portion of the frame which supports the magazine,

10 which wires are parallel to one another at a distance apart slightly less than the smaller end of the cup. Down these guide wires 49 the cup falls and is diverted forward to a position immediately under the delivery 15 spout 19 of the measuring cylinder 18, at which position the cup is received and its flanged upper edge rests on two wires 50 bent to conform to the curvature of the cup flange. These wires 50 are pivotally mounted on a common pin 51 and the after end of each wire 50, beyond the pivot 51, is outwardly turned to the same side as its bend 50, and is upwardly turned as at 52 to enter a transverse slot 53 formed on the end of a rod 54 slidably mounted to move endwise in bearings 56 on a member 57 which is itself endwise movable in guideways 58 parallel to the rod 54.

The end of the rod 54 is downwardly 20 turned to pass through an open ended slot 59 in the backward end of the slidable member 57 and below that member is angled toward the original alignment of the rod 54, as at 55, for a purpose to be explained later.

25 The member 57 is endwise movable in slideways 58 to transfer the cup carried in the supports 50 from its position under the measuring cylinder 18 to a position, shown in dot and dash lines in Figs. 1, 11 and 12, 40 from which it can be lifted upward for presentation to the vendee.

Endwise movement of the member 57 is effected by the following means: Immediately under the shorter end 16 of the lever 13 is a bell crank lever 60, 61 which is pivotally mounted at 62 in a member secured to and projecting upward from the base of the frame 2. The shorter arm 61 of this lever is connected by a spring 63 to the end 16 of the 50 lever 13 and the upper end of the arm 60 of the bell crank lever is connected by a link 64 to a rod 65 which is secured across the backward end of the slidable member 57, so that as the operating lever 13 is moved down 55 to the position indicated by the dot and dash lines in Fig. 1, by downward movement of the external handle 5 in the manner previously described, tension is imposed on the spring 63, which tension tends to turn the bell crank lever on its pivot 62 and project the slidable member 57 with the cup 33 supported on the members 50 forward to the position represented by the dot and dash lines.

60 To check this forward movement of the filled cup that it may move at a moderate

velocity, a rod 66 is secured to the after end of the member 57 and projects parallel therewith and its forward end passes into a tube 67 secured to the slideway 58. As the forward end of this tube 67 is closed, the air 70 within it forms an elastic check to movement of the member 57, the air leaking gradually past the fit of the rod 66 in the tube as the tension of the spring 63 exerts itself.

To ensure that the member 57 does not 75 move forward until the liquid in the cylinder 18 has been discharged into the cup 33, and the cup lifting mechanism, to be described later, is clear of the cup's forward movement, the lever 61 is latched at the 80 lower limit of its movement by a hook formed on the shorter arm of a bell crank lever 68 pivoted at 69 and released in a manner to be described later.

The filled cup is presented to the vendee 85 through an aperture 71 in a horizontally disposed ledge or counter of the frame 2. This aperture 71 is normally closed by a plate 72 slidably mounted on a guide 73 secured to the frame within the casing and upwardly 90 and downwardly moved by the longer end of the lever 13, an open slot in the end of which engages a pin 74 secured to the plate 72 or attached part thereof. On the upper side of the plate 72 is a shallow, cuplike receptacle 75 which projects through the aperture 71 when the plate closes that aperture.

Downward movement of the external lever 5, when the same is connected to the internal mechanism by the deposit of a coin 100 in the manner described, moves down the lever 13 and with it the plate 72 to adjacent the bottom of the casing, leaving a clear space above the cup 75 immediately opposite the position of a filled cup 33. To 105 retain this lever 13 in the downward position while the filled cup is being moved forward into the upward path of the plate 72, the shorter opposite end 16 of this lever is latched by a hook latch 76 pivoted at 77 110 to a member attached to the frame 2, the upper end of which hook member projects upward as at 78 to be engaged and the latch released by any suitable projection from the cup holding slide member 57. In 115 the drawing it is shown as engaged by the forwardly turned end 79 of the rod 65, by which connection is made to move that member. Thus, when the slidable member 57 is moved forward to transfer the filled 120 cup from its normal position under the filling spout to a position ready for presentation, as indicated by the dot and dash lines, the end 78 of the hook latch 76 is engaged and that latch released, setting free the lever 13 to elevate the plate 72 under the tension of the spring 15, and checked by the synchronous movement of the piston 22 in the cylinder 18 while recharging the cylinder. 125

As the filled cup 33 stands in the path of the upward movement of the plate 72, the filled cup is lifted in its receptacle 75 and is projected through the aperture 71 for the vendee.

The means was described by which the member 57 with the filled cup in the supports 50 was projected forward into the position indicated by dot and dash lines. 10 That means was actuated by the tension of a stressed spring with provision to avoid precipitate movement. For that reason a separate means must be provided for returning the same after the supporting members 50 have been opened to free them from the cup.

This means comprises a lever 80 bent from wire to have a cam outline somewhat as shown in Figs. 1 and 11. One end of this 20 lever 80 is secured to the shaft 4 to move with it and the other end 81 is turned across under the plane of movement of the slidable member 57 which carries the cup supports 50. During the downward movement 25 of the handled lever 5 this lever 80 is moved upward to the position indicated by the dot and dash lines in Fig. 11, with the end 81 adjacent the underside of 57 and the rearward end of the slideway 58 of that member. Later, when the slidable member 57 is moved forward under the influence of the spring 63, the tension on which was imposed by the same downward movement, the 30 forwardly turned end 55 of the rod 54 is moved up to the position indicated. When the shorter arm 16 of the lever 13 is released and under the influence of the spring 15, the lever 80 secured to the same shaft moves down with it. During the first part 35 of the movement, the end 81 engages the forwardly directed end 55 of the rod 54 and moves that rod to the position indicated by the double dot and dash lines, in which movement the ends 52 of the cup supporting members 50 are drawn together to open the members 50 from engagement with the cup, as shown in Fig. 12. Thereafter the cam formed outline of the lever 80 engages the rod 65 secured in the slidable member 40 57 and moves that member back to its normal position with the centre of the members 50 under the cylinder 18, and at the latter end of this movement the upwardly turned ends 52 of the cup holding members engage a transverse block 82 by which they are moved apart in the slot 53 and close the members 50 to receive the next cup released from the magazine.

The release of a cup from the magazine, 45 as previously described, must be coincident with the completion of the backward movement of the slidable member 57 in order that the cup supports 50 carried by that member may be in position when the cup is released.

The lever 41, by which the cup release from the magazine is operated, extends angularly backward and downward to a position adjacent the after end of the slidable member 57 at the backward limit of its 70 movement, and freely pivoted in the end of this lever 41 is a short equal armed lever 53, the upper end of which is stopped against a projection adjacent the pivot and the other end of which is weighted that it 75 may normally maintain an upright position against this stop with its lower end projecting in the path of one of the bearing members 56 of the rod 54.

While the member 57 is moved forward to the position of presentation, 56 may pass freely under the member 83, as shown by the dot and dash lines in Fig. 1, but during the return movement of the member 57 the member 56 engages the lower end of 83 and operates the lever 41 to effect release of a cup from the magazine in the manner described. The lever 41 is then restored to its normal position by the springs 44.

In describing the means for forwardly moving the slidable member 57 a means was described for retaining the operative mechanism by which the movement was effected, while the cup 33 was filled from the cylinder 18 and the presenting plate 72 was moved downward clear of the path of the cup carried by the member 57.

The bell crank 60, 61 by which the slidable member 57 is moved forward was shown as latched by a small bell crank 68 having a hook end to engage the shorter arm 61 of the operating bell crank. The longer arm of the bell crank 68 has a rod 70 pin-connected to it, the upper end of which passes through an aperture in the produced end of the lever 28 by which the cylinder piston is operated, and the upper end of the rod is bent over or has a button end on it to be engaged by the end of the lever 28 adjacent the upper limit of that lever's movement, and draws up the bell crank lever 68 to effect release of the bell crank 60, 61 under the influence of its spring 63. This release being operative by the mechanism which actuates the expression of the liquid from the cylinder, ensures that the expression terminates before the cup 33 is moved from under the spout to the position for presentation.

To ensure that a hasty or over-forceful pull on the handle lever 5 will not subject the charging mechanism of the measuring cylinder to undue strain, the connecting rod 31 between the shorter end 16 of the internal operating lever 13 is not positively connected to the lever 28 by which the piston of the measuring cylinder is moved, but is slidable through an aperture in the end of that lever, and a spring 32 is coiled on the rod 31 between the connection of that rod 125 110 115 120 125 130

to 16 and the underside of the lever 28. Any undue pressure thus exerted on the handle lever 5 will place the spring 32 under compression, which compression will exert itself later to effect the required movement of the piston 22.

All the movements of the machine are carefully regulated to be synchronous or timed in relation to the other movements 10 dependent on them.

The entire operation of the machine may be generally described as follows:

On deposit of a coin of the required size in the slot 11, connection is made in the manner described between the external handled lever 5 with the operating shaft 4 in the machine and the various parts secured thereto. Downward movement of the lever 5, in the direction shown on Fig. 1, will draw 15 downward the presentation plate 72 with its cup holding receptacle 75: Will express the charged contents of the cylinder 18 through the elasticity of the spring 32, into the cup previously released from the magazine and 20 supported in position beneath: Will move the lever 80 to bring its end 81 into the position show in dot and dash lines in Fig. 11, where it will, during the return movement, engage the downwardly turned end 25 55 and withdraw the supports 50 from the cup: Will impose the required tension on the springs 15 and 63 to perform the other movements, and in the latter part of its movement will effect release of the bell 30 crank lever 60, 61, to perform their service under the tension of the spring 63, that is, to transfer the filled cup from under the charging cylinder 18 to a position beneath the aperture 71 and in the path of the drawn down plate 72.

Thereafter the handle 5 on being released will be carried up to its normal upper position by the spring 12 independent of the operation of the internal mechanism of the machine, the principal operating lever 13 of which is latched at the downward limit of its movement. As explained the movement of the lever 28 which controls other movements will necessarily be slower under the 50 action of the spring 32 owing to the resistance offered by the liquid being expressed from the cylinder; but when the lever 28 reaches the upper limit of its movement under the pressure of the spring 32, the bell crank lever 60, 61 is released and under the tension imposed on its spring 63 and checked by the air cushion in the tube 67, the member 57 is moved slowly forward carrying the filled cup to the position ready for presentation through the aperture 71. At the conclusion of this movement the latch 76 is released and the lever 13 is free to move up under the action of the spring 15, lifting the filled cup with it on the plate 72. At the same time the rod 54 is drawn back by the

end 81 of the lever 80 to release the filled cup from its support on the members 50 and the member 57 and those supports 50 are withdrawn clear of the uplifting plate 72. Near the conclusion of this movement the after projection 56 carries with it the lower end of the lever 41, and operates the cup release mechanism to set free another cup from the magazine and deliver it into the supports 50 in position beneath the measuring cylinder 18.

While the lever 13 is moving up under the action of the spring 15, its movement is checked by the movement of the piston 22, recharging the measuring cylinder 18, the operating mechanism of the piston 22 being connected to the shorter arm 16 of 13.

When the lever 13 is latched at the downward limit of its movement and the external handled lever 5, by which the lever 13 was 25 carried down, moves toward its normal upward position, it moves the tongue 8 off the coin in the chute extension 14 and the coin, which connects the two levers, falls into the cash receptacle.

I do not desire to be confined to the particular construction and manner of operation of the several parts of the machine, as set forth in this specification, or as illustrated in the drawings by which it is accompanied, as the same may require to be varied considerably to meet the requirements of manufacture: Further, the customary provision will require to be made for detecting and rejecting an unsuitable coin or for preventing the use of slugs.

Having now particularly described my invention, I hereby declare that what I claim as new and desire to be protected in by Letters Patent, is:

1. A soft drink vending machine, comprising the combination with a suitable casing of a liquid supply reservoir, a cup containing magazine, and means operative from without the casing for withdrawing a cup 110 from the magazine, for delivering a measured quantity of liquid from the reservoir into the cup, and for delivering the filled cup through a closable opening to without the casing.

2. A liquid vending machine, comprising the combination with a suitable casing, of a liquid supply reservoir, a cup containing magazine wherein the cups are supported by the flanged upper edge of the lower cup 120 in the magazine, means within the casing and operative from without the casing for withdrawing the support from the edge of the lower cup and for simultaneously projecting a support beneath the flange of the next cup above it, and means cooperative with such movement for withdrawing the released cup from the others in the magazine and for delivering it beneath the liquid delivery, means for delivering a measured 125 130

- quantity of the liquid into the cup, and means for delivering the filled cup through a closable aperture in the casing.
3. A liquid vending machine, comprising the combination with a suitable casing, of a liquid supply reservoir, a measuring cylinder connected through a check valve with the supply reservoir, a cup containing magazine, a mechanism within the casing for releasing a cup from the magazine and for placing it beneath the measuring cylinder, for expressing the contents of the measuring cylinder into the cup, for delivering the filled cup through a closable aperture in the casing, a handle without the casing connected with the mechanism within the casing, and means for connecting the external handle with the operative mechanism within the casing.
- 10 4. A liquid vending machine, comprising the combination with a suitable casing, of a liquid supply reservoir, a measuring cylinder, one end of which is connected to the reservoir through a check valve closing toward the reservoir and is provided with a delivery spout having a spring loaded valve opening outward, a piston endwise movable in the cylinder, a cup containing magazine, an operative mechanism within the casing for releasing a cup from the magazine and effecting its transfer to a position beneath the spout of the measuring cylinder, for moving the piston to express the contents of the measuring cylinder into the cup, for recharging the measuring cylinder, for transferring the filled cup from its position under the measuring cylinder to a position for presentation through a closable aperture in the casing, and means for delivering the filled cup through said aperture in the casing and means without the casing for operating the mechanism within the casing.
- 15 5. A liquid vending machine, comprising the combination with a suitable casing, of a liquid supply reservoir, means for delivering a measured quantity of liquid from the reservoir into a cup, means for supporting a cup beneath the delivery spout, means for projecting the cup supports forward for presentation of the filled cup to the vendee, means for withdrawing the cup supports from engagement with the cup, and means for returning them to their normal supporting position beneath the delivery spout.
- 20 6. A liquid vending machine, comprising the combination with a suitable casing having an aperture through which a filled cup of liquid may be presented to the vendee, a liquid supply reservoir, means within the casing for delivering a measured quantity of liquid into a cup, means for supporting the cup beneath the liquid delivery, a plate within the casing closing the delivery aperture thereof, means for supporting the cup on the outer side of the closing plate, means for transferring the cup from its position beneath the filling spout to its position on the aperture closing plate, and means for moving the plate to deliver the cup and to close the aperture.
- 25 7. A liquid vending machine, comprising the combination with a suitable casing having an aperture through which a filled cup of liquid may be presented to the vendee, a liquid supply reservoir, means within the casing for delivering a measured quantity of liquid into a cup, means for supporting the cup beneath the liquid delivery, a plate within the casing closing the delivery aperture thereof, means for supporting the cup on the outer side of the closing plate, means for transferring the cup from its position beneath the filling spout to its position on the aperture closing plate, and means for moving the plate to deliver the cup and to close the aperture.
- 30 8. A liquid vending machine, comprising the combination with a suitable casing, of a liquid supply reservoir, a measuring cylinder to one end of which the supply reservoir is connected, said measuring cylinder having a delivery spout with a spring loaded valve retaining the contents in the cylinder, a check valve in the reservoir connection, a piston endwise movable in the cylinder, a cup holding magazine, means for releasing the lower cup from the magazine and for delivering it to a position beneath the spout of the measuring cylinder, means for lifting a filled cup for delivery through an aperture in the casing, means for transferring the cup from beneath the measuring cylinder to a position in the path of the lifting means, a rocking shaft within the casing, a handle without the casing releasably connected to the shaft within the casing, means operatively connecting the external handle with the rocking shaft on delivery of a suitable coin within the casing, means for normally maintaining the external handle at one limit of its movement, means for normally maintaining the rocking shaft at the corresponding limit of its movement, means for latching the internal mechanism connected to the rocking shaft at the opposite limit of its movement, a spring connected to the rocking shaft on which tension is imposed by movement of the external handle from the normal position, means for connecting the piston
- 35 9. A liquid vending machine, comprising the combination with a suitable casing having a delivery opening and a cup lifting means associated with said opening, of a liquid supply reservoir, means for delivering a measured quantity of liquid from the reservoir to a cup, a horizontally slidable member having opposed cup supports pivotally mounted on the slidable member, the inner ends of which cup supports are turned to engage a transversely elongated slot in a member endwise movable parallel with and independent of the slidable member, means for moving the slidable member forward to transfer the cup from its position under the delivery spout to its position under the lifting means, means for moving the slidable member backward to its normal position with the centre of the cup support under the delivery spout, means cooperative with the initial part of such backward movement for simultaneously withdrawing the cup supports from their position of engagement with the cup, and means for restoring the cup supporting members to their cup supporting position on arrival of them beneath the delivery spout.
- 40 10. A liquid vending machine, comprising the combination with a suitable casing having a delivery opening and a cup lifting means associated with said opening, of a liquid supply reservoir, means for delivering a measured quantity of liquid from the reservoir to a cup, a horizontally slidable member having opposed cup supports pivotally mounted on the slidable member, the inner ends of which cup supports are turned to engage a transversely elongated slot in a member endwise movable parallel with and independent of the slidable member, means for moving the slidable member forward to transfer the cup from its position under the delivery spout to its position under the lifting means, means for moving the slidable member backward to its normal position with the centre of the cup support under the delivery spout, means cooperative with the initial part of such backward movement for simultaneously withdrawing the cup supports from their position of engagement with the cup, and means for restoring the cup supporting members to their cup supporting position on arrival of them beneath the delivery spout.
- 45 11. A liquid vending machine, comprising the combination with a suitable casing having a delivery opening and a cup lifting means associated with said opening, of a liquid supply reservoir, means for delivering a measured quantity of liquid from the reservoir to a cup, a horizontally slidable member having opposed cup supports pivotally mounted on the slidable member, the inner ends of which cup supports are turned to engage a transversely elongated slot in a member endwise movable parallel with and independent of the slidable member, means for moving the slidable member forward to transfer the cup from its position under the delivery spout to its position under the lifting means, means for moving the slidable member backward to its normal position with the centre of the cup support under the delivery spout, means cooperative with the initial part of such backward movement for simultaneously withdrawing the cup supports from their position of engagement with the cup, and means for restoring the cup supporting members to their cup supporting position on arrival of them beneath the delivery spout.
- 50 12. A liquid vending machine, comprising the combination with a suitable casing having a delivery opening and a cup lifting means associated with said opening, of a liquid supply reservoir, means for delivering a measured quantity of liquid from the reservoir to a cup, a horizontally slidable member having opposed cup supports pivotally mounted on the slidable member, the inner ends of which cup supports are turned to engage a transversely elongated slot in a member endwise movable parallel with and independent of the slidable member, means for moving the slidable member forward to transfer the cup from its position under the delivery spout to its position under the lifting means, means for moving the slidable member backward to its normal position with the centre of the cup support under the delivery spout, means cooperative with the initial part of such backward movement for simultaneously withdrawing the cup supports from their position of engagement with the cup, and means for restoring the cup supporting members to their cup supporting position on arrival of them beneath the delivery spout.
- 55 13. A liquid vending machine, comprising the combination with a suitable casing having a delivery opening and a cup lifting means associated with said opening, of a liquid supply reservoir, means for delivering a measured quantity of liquid from the reservoir to a cup, a horizontally slidable member having opposed cup supports pivotally mounted on the slidable member, the inner ends of which cup supports are turned to engage a transversely elongated slot in a member endwise movable parallel with and independent of the slidable member, means for moving the slidable member forward to transfer the cup from its position under the delivery spout to its position under the lifting means, means for moving the slidable member backward to its normal position with the centre of the cup support under the delivery spout, means cooperative with the initial part of such backward movement for simultaneously withdrawing the cup supports from their position of engagement with the cup, and means for restoring the cup supporting members to their cup supporting position on arrival of them beneath the delivery spout.
- 60 14. A liquid vending machine, comprising the combination with a suitable casing having a delivery opening and a cup lifting means associated with said opening, of a liquid supply reservoir, means for delivering a measured quantity of liquid from the reservoir to a cup, a horizontally slidable member having opposed cup supports pivotally mounted on the slidable member, the inner ends of which cup supports are turned to engage a transversely elongated slot in a member endwise movable parallel with and independent of the slidable member, means for moving the slidable member forward to transfer the cup from its position under the delivery spout to its position under the lifting means, means for moving the slidable member backward to its normal position with the centre of the cup support under the delivery spout, means cooperative with the initial part of such backward movement for simultaneously withdrawing the cup supports from their position of engagement with the cup, and means for restoring the cup supporting members to their cup supporting position on arrival of them beneath the delivery spout.
- 65 15. A liquid vending machine, comprising the combination with a suitable casing having a delivery opening and a cup lifting means associated with said opening, of a liquid supply reservoir, means for delivering a measured quantity of liquid from the reservoir to a cup, a horizontally slidable member having opposed cup supports pivotally mounted on the slidable member, the inner ends of which cup supports are turned to engage a transversely elongated slot in a member endwise movable parallel with and independent of the slidable member, means for moving the slidable member forward to transfer the cup from its position under the delivery spout to its position under the lifting means, means for moving the slidable member backward to its normal position with the centre of the cup support under the delivery spout, means cooperative with the initial part of such backward movement for simultaneously withdrawing the cup supports from their position of engagement with the cup, and means for restoring the cup supporting members to their cup supporting position on arrival of them beneath the delivery spout.

- of the measuring cylinder to the rocking shaft to express the contents of the cylinder during movement of the external handle from its normal position, a spring connection between the rocking shaft and the transfer mechanism of the cup from beneath the measuring cylinder to the path of the lifting means, means for retaining that mechanism in its normal position beneath the measuring cylinder, means for releasing said retaining means at the end of the expression movement of the piston, means directly connected to the rocking shaft for moving down the cup lifting means during movement of the rocking shaft from its normal position and for lifting the same when the retaining means of the internal mechanism is released.
9. In a liquid vending machine, a casing having a delivery aperture, a measuring cylinder and its piston, a magazine for nested cups, a handled lever, means operated by the movement of such lever in one direction for effecting the action of said piston and measuring cylinder to express the contents thereof into a previously positioned cup beneath the cylinder, means operated on further movement of the lever in such one direction for moving the filled cup from beneath the measuring cylinder into position in alignment with the delivery aperture of the casing, means for moving said lever in an opposite direction to elevate and deliver the charged cup through said aperture, operate the parts to recharge the measuring cylinder and release a cup from the magazine and place it in position beneath said cylinder, substantially as shown and described.
10. In a liquid vending machine, a casing having a delivery aperture, means normally closing said delivery aperture, a measuring cylinder with piston for receiving charges of liquid to be dispensed, a paper cup magazine, an operating lever, mechanism operated by said lever when moved in one direction for simultaneously operating said piston to express a charge of liquid into a previously positioned cup beneath the same, uncover said delivery aperture of the casing and upon further movement in said one direction move the filled cup from beneath the measuring cylinder into position beneath the delivery aperture, and mechanism for restoring said lever to its initial position and simultaneously elevating the filled cup through said delivery aperture and moving said piston to recharge the cylinder and place another cup in position beneath the cylinder substantially as specified.

In testimony whereof I affix my signature.
JAMES H. McLELLAN.
